CLAIM

The ornamental design for a heart shaped dispenser, as shown and described.

DESCRIPTION

FIG. 1 is a perspective view showing the new design for a heart shaped dispenser;

FIG. 2 is a left side view thereof, the right side view being a mirror image thereof;

FIG. 3 is a front view thereof;

FIG. 4 is a rear view thereof;

FIG. 5 is a top view thereof; and,

FIG. 6 is a bottom view thereof.

The broken lines showing the slot in the top surface in FIGS. 1, 2, 3 and 5 are included for the purpose of illustrating a feature that forms no part of the claimed design.
